CLAIM

The ornamental design for a display screen or portion thereof with graphical user interface for displaying software cells, as shown and described.

DESCRIPTION

FIG. 1 is a front view of the first embodiment of the display screen or portion thereof with graphical user interface for displaying software cells;

FIG. 2 is a front view of a patently indistinct second embodiment of the display screen or portion thereof with graphical user interface for displaying software cells; and, FIG. 3 is a front view of a patently indistinct third embodiment of the display screen or portion thereof with graphical user interface for displaying software cells.

The broken lines showing a display screen, text, and portions of the graphical user interface form no part of the claimed design.

1 Claim, 3 Drawing Sheets

FIG. 1

FIG. 2

FIG. 3
